UNITED STATES PATENT OFFICE.

LESLIE R. ALLISON, OF LA CROSSE, WISCONSIN, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed June 8, 1925. Serial No. 35,561.

My invention relates to railway traffic controlling apparatus, and particularly to apparatus of the type comprising train carried governing means controlled in accordance with traffic conditions.

I will describe two forms of apparatus embodying my invention, and will then point out the novel features thereof in claims.

In the accompanying drawing, Fig. 1 is a diagrammatic view showing one form of railway traffic controlling apparatus embodying my invention. Fig. 2 is a view showing a modified form of the apparatus illustrated in Fig. 1 and also embodying my invention.

Similar reference characters refer to similar parts in both views.

Referring first to Fig. 1, the apparatus comprises a pipe 1 normally supplied with fluid pressure, usually air, and arranged to apply the brakes when the pressure in this pipe is reduced. Under normal conditions pipe 1 is connected through a cut-out valve C and pipe 9 with an application valve D. Valve D comprises a valve body 10 containing a plunger 11 controlled by traffic conditions in advance by means forming no part of my present invention and omitted from the drawing for the sake of simplicity. Under safe traffic conditions plunger 11 is drawn upwardly, thereby disconnecting pipe 9 from port 12 which is in communication with atmosphere. When traffic conditions in advance are dangerous and the speed of the train is above a predetermined maximum plunger 11 is moved downwardly and pipe 9 is then connected with atmosphere through port 12. It will be plain that when valve C is open to permit communications between pipe 1 and pipe 9, the brakes will be applied if valve D is open.

Valve C comprises a valve body 2 containing an operating cylinder 6 communicating with atmosphere through a restrictive orifice 7. A piston 3 has its lower face exposed to the pressure in cylinder 6 and is normally biased to a lower position by a spring 4. Piston 3 carries a valve 5 which is arranged to close pipe 1 when piston 3 is moved to its upper position but to connect pipe 1 with pipe 9 when piston 3 occupies its lower position under the influence of spring 4. The cut-out valve C is controlled

by a manual operable acknowledging valve A and a repeater relay B.

The repeater valve B comprises a valve body 15 divided into a pressure chamber 18 and an operating chamber 17 by a reciprocable piston 16. A spring 21 constantly urges the piston 16 to its right hand position, but fluid pressure supplied to the pressure chamber through pipe 19 from some suitable source not shown in the drawing, normally urges the piston 16 to the left against the pressure exerted by spring 21. The piston 16 operates a slide valve 20. When piston 16 is in its left hand position valve 20 connects a reservoir K through pipes 26 and 25, port 23 and pipe 22 with a source of fluid pressure not shown in the drawing. When piston 16 is moved to the right, as will be explained hereinafter, reservoir K is disconnected from pipe 22 and is connected through pipes 26 and 25, port 23 with pipe 8. Pipe 8 is constantly connected with operating cylinder 6 of cut-out valve C and is also constantly connected, through pipe 27, with operating chamber 17 of repeater valve B.

The acknowledging valve A comprises a valve body 28 containing a valve 29 which is normally held in its closed position by a spring 31. When the pivoted handle 30 is moved toward the left a piston 33 is moved against the bias of a spring 31 to open valve 29, thereby connecting pipe 26 with pipe 32. Pipe 32 communicates with the operating chamber 17 of valve D and with pipe 27, which has already been described.

As shown in the drawing all parts of the apparatus are illustrated in their normal conditions, that is, application valve D is closed, and acknowledging valve A is also closed. The operating cylinder 6 of valve C is connected with atmosphere through port 7 so that piston 3 of valve C is in its lower position allowing communication between pipes 1 and 9. Operating chamber 17 of valve B is also connected to atmosphere through pipes 27 and 8 and port 7, so that piston 16 of valve B is held in its left hand position against the bias of spring 21 by pressure in chamber 18. Reservoir K is therefore charged with fluid pressure from pipe 22. If, under these conditions, application valve D is opened, pipe 1 is vented to

atmosphere through valve C, pipe 9 and port 12 and an application of the brakes results. If, however, prior to the opening of valve D, handle 30 of acknowledging valve A is operated, the opening of valve 29 connects reservoir K through pipe 26, valve 29, and pipe 32 with the operating chamber of valve B. At the same time pressure from reservoir K is supplied through pipe 27 and pipe 8 to the 10 operating cylinder 6 of valve C. This pressure in operating cylinder 6 moves piston 3 upwardly and closes pipe 1. It will be plain that opening of valve D can now have no effect upon the brakes. The pressure supplied to operating chamber 17 from reservoir K together with the force exerted upon piston 16 by spring 21 combine to move the piston 16 to the right hand position against the force exerted by the pressure existing in 15 chamber 18. Valve 20 is shifted to the right and reservoir K is therefore disconnected from pipe 22 and is connected directly with pipe 8, and hence with chamber 17 of valve B and cylinder 6 of valve C. As soon as the 20 handle 30 of valve A is released spring 31 again closes the valve 29 so that pipe 26 is disconnected from pipe 32. But reservoir K is now connected directly with pipe 8, so that piston 16 remains in its right hand position and piston 3 of valve C remains in its 25 upper position to prevent an automatic application of the brakes should valve D be opened. The pressure in reservoir K is gradually dissipated to atmosphere through the restricted orifice 7 in valve C. After the 30 expiration of a time interval the pressure in chamber 6 is so reduced that spring 4 returns piston 3 to its lower position and the brakes will then be applied if valve D is open. The 35 pressure in chamber 17 of valve B is also reduced by dissipation through orifice 7 in valve C and after the expiration of the time interval mentioned above the pressure in chamber 17 is so reduced that the force exerted by pressure in chamber 18 restores piston 16 to its left hand position against the combined force of spring 21 and the 40 reduced pressure existing in chamber 17. This motion of piston 16 disconnects the reservoir K from pipe 8 and again connects the reservoir with pipe 22. The apparatus is therefore automatically restored to its initial condition.

50 Referring now to Fig. 2 the cut-out valve C and the application valve D are the same as in Fig. 1, but the repeater valve B is replaced by a valve B' incorporated in the valve body 28 of the acknowledging valve A. The acknowledging valve comprises a valve 55 29 normally closed by a spring 31 but arranged to be opened by operation of handle 30 through the medium of a plunger 33. Valve body 28 also contains a piston 35 60 which is constantly urged to the left by a spring 36. Reservoir K is constantly con-

nected through pipe 26 and port 39 with valve 29, and pipe 26 also communicates with two ports 38 and 40 controlled by piston 35. Fluid pressure is supplied to the left hand face of piston 35 through pipe 37, and the right hand side of piston 35 is connected with pipe 8. A port 34 communicating with pipe 8 is connected to the right hand side of valve 29.

Under normal conditions, that is when 75 valve 29 is closed, reservoir K is disconnected from pipe 8, so that piston 3 of cut-out valve C is in its lower position. Under these conditions fluid pressure from pipe 37 holds piston 35 to the right thereby uncovering port 38 and supplying pressure to reservoir K. When handle 30 of valve A is operated to open valve 29, pressure flows from reservoir K through pipe 26 and port 39, valve 29, port 34 and pipe 8 to operating cylinder 6 of valve C, thereby moving piston 3 of valve C upwardly to close pipe 1. At the same time pressure thus supplied to pipe 8 combines with spring 36 to move piston 35 to the left, thereby disconnecting reservoir K 80 from pipe 37 and connecting this reservoir directly with pipe 8 through port 40. When handle 30 of valve A is released piston 35 is retained in its left hand position by pressure from reservoir K until this pressure is dissipated to atmosphere through orifice 7 of valve C. After the time interval required for this reduction in the pressure in reservoir K, piston 3 of valve C is restored to its lower 85 position by spring 4, and piston 35 of valve B' is restored to its right hand position by pressure from pipe 37. The parts of the apparatus are therefore automatically restored to their original positions.

In both forms of the apparatus herein shown and described it will be seen that operation of the acknowledging valve A actuates the cut-out valve C to render the automatic application valve D ineffective for an interval of time to apply the brakes. It will also be seen that the apparatus is so arranged that the acknowledging valve may be immediately released and that the cut-out valve will not return to its initial position until the expiration of a fixed time interval.

One advantage of this feature is that the engineman may acknowledge a change in traffic conditions by manipulation of valve A and may then direct his attention exclusively to the operation of his train. The apparatus is so designed as to be automatically restored to its initial condition after the expiration of a time interval independent of any further attention on the part of the engineman.

Although I have herein shown and described only two forms of railway traffic controlling apparatus embodying my invention, it is understood that various changes and modifications may be made therein with-

in the scope of the appended claims without departing from the spirit and scope of my invention.

Having thus described my invention, what I claim is:

1. In combination, apparatus on a train for causing an application of the brakes, automatic means for actuating such apparatus, a first valve arranged when supplied with fluid pressure to render said automatic means ineffective to apply the brakes, a reservoir, a second valve normally connecting said reservoir with a source of fluid pressure, a manually operable valve for connecting said reservoir with said first valve and for operating said second valve to disconnect the reservoir from said source, and means incorporated in said first valve for gradually reducing the pressure in said reservoir so that after the expiration of a time interval said second valve is restored to its initial condition.

2. In combination, apparatus on a train for causing an application of the brakes, automatic means for actuating such apparatus, a cylinder connected with atmosphere through a restricted orifice and containing a piston biased to a position in which said automatic means is effective to apply the brakes, a reservoir, a first valve biased to a position in which said reservoir is connected with a source of fluid pressure, a manually operable self restoring valve for connecting said reservoir with said cylinder to move said piston into a position wherein said automatic means is ineffective to apply the brakes and for also connecting said reservoir with said first valve to disconnect said reservoir from said source and to connect the reservoir directly with said cylinder.

3. In combination, apparatus on a train for causing an application of the brakes, automatic means for actuating such apparatus, a cylinder connected with atmosphere through a restricted orifice and containing a piston biased to a position in which said automatic means is effective to apply the brakes, a valve comprising two chambers, a reservoir, means for constantly supplying fluid pressure to one of said chambers for biasing said valve to a position in which said reservoir is connected with a source of fluid pressure, and a normally closed manually operable valve for connecting said reservoir with said cylinder to move said piston into a position wherein said automatic means is ineffective to apply the brakes and for also connecting said reservoir with the second chamber of said valve to move the valve to a second position wherein said reservoir is disconnected from said source and is connected

directly with said cylinder and with said second chamber.

4. In combination, a valve on a train for controlling the brakes and comprising an operating cylinder connected with atmosphere through a restricted orifice, a reservoir, a second valve comprising two chambers separated by a reciprocable piston, means for constantly supplying one of said chambers with fluid pressure so that the piston normally occupies one extreme position, a slide valve controlled by said piston and normally connecting said reservoir with a source of fluid pressure, and a manually operable valve for connecting said reservoir with said operating cylinder and with the second said chamber so that the piston is moved to its other extreme position and the slide valve then disconnects said reservoir from said source and connects the reservoir directly with said operating cylinder.

5. In combination, a valve on a train for controlling the brakes and comprising an operating cylinder connected with atmosphere through a restricted orifice, a reservoir, a second valve comprising an operating chamber constantly connected with said operating cylinder, said second valve normally connecting said reservoir with a source of fluid pressure, and a manually operable valve for at times connecting said reservoir with said operating cylinder and with said operating chamber so that said second valve operates to disconnect said reservoir from said source and to connect the reservoir directly with said operating cylinder and with said operating chamber.

6. In combination, a valve on a train for controlling the brakes and comprising an operating cylinder connected with atmosphere through a restricted orifice, a reservoir, a second valve comprising two chambers separated by a reciprocable piston, means for constantly supplying fluid pressure to one said chamber, means for constantly connecting the other said chamber with said cylinder, a slide valve controlled by said piston and normally occupying a position in which said reservoir is connected with said source, and a manually operable valve for connecting said reservoir with the operating cylinder of said first valve and with said other chamber, whereby said piston is shifted to move the slide valve to a different position in which said reservoir is connected directly with the operating cylinder of said first valve and with said other chamber.

In testimony whereof I affix my signature.

LESLIE R. ALLISON.
